(57) **CLAIM**

The ornamental design for a cover for an engine control unit, as shown and described.

DESCRIPTION

FIG. 1 is an upper perspective view of a design for a cover for an engine control unit;

FIG. 2 is a lower perspective view of the design of FIG. 1;

FIG. 3 is a top view of the design of FIG. 1;

FIG. 4 is a bottom view of the design of FIG. 1;

FIG. 5 is a first side view of the design of FIG. 1;

FIG. 6 is a second side view of the design of FIG. 1;

FIG. 7 is a front view of the design of FIG. 1; and,

FIG. 8 is a rear view of the design of FIG. 1.

The broken lines shown in the drawings are included for the purpose of illustrating the unclaimed boundary or unclaimed portions of the cover for an engine control unit. The broken lines form no part of the claimed design.
